ELECTRIC RANGE

Charles A. Pierson, Maumee, Ohio

Application April 30, 1948, Serial No. 146,069

Term of patent 14 years

(Cl. D81—4)

To all whom it may concern:

Be it known that I, Charles A. Pierson, a citizen of the United States and resident of Maumee, in the county of Lucas, and State of Ohio, have invented a new, original, and ornamental Design for an Electric Range, of which the following is a specification, reference being had to the accompanying drawing, forming a part thereof.

In the drawing, Fig. 1 is a front elevation of a range embodying my new design; Fig. 2 is an elevation of one side thereof with the surface burner door in open position, and Fig. 3 is a top plan view of the range. Both sides of the range present the same appearance.

I claim:

The ornamental design for an electric range substantially as shown and described.

CHARLES A. PIERSON.
